(57) **CLAIM**

The ornamental design of a duster with an extendable handle, as shown and described.

DESCRIPTION

FIG. 1 is a perspective view of the duster with extendable handle in use.

FIG. 2 is a perspective view of the duster with extendable handle.

FIG. 3 is a right side view of the duster with extendable handle.

FIG. 4 is a rear view of the duster with extendable handle.

FIG. 5 is a left side view of the duster with extendable handle.

FIG. 6 is a front view of the duster with extendable handle.

FIG. 7 is a top view of the duster with extendable handle; and,

FIG. 8 is a bottom view of the duster with extendable handle.

The handle is shown fragmented in FIGS. 2-6 to indicate non-specified length.
